CLAIM

The ornamental design for an overcap and container assembly, as shown and described.

DESCRIPTION

FIG. 1 is an isometric view of a top, front, and left side of an ornamental design for an overcap and container assembly; FIG. 2 is a front elevational view of the overcap and container assembly of FIG. 1;

FIG. 3 is a rear elevational view of the overcap and container assembly of FIG. 1;

FIG. 4 is a left side elevational view of the overcap and container assembly of FIG. 1;

FIG. 5 is a right side elevational view of the overcap and container assembly of FIG. 1; and,

FIG. 6 is a top plan view of the overcap and container assembly of FIG. 1.

The broken lines are for the purpose of illustrating environmental structure and form no part of the claimed design.
